TELEPHONE HANDSET SUPPORT

Edward A. Praisner, Montclair, N.J., assignor to Bell Telephone Laboratories, Incorporated, New York, N.Y., a corporation of New York

Filed June 28, 1963, Ser. No. 75,581

Term of patent 14 years

(Cl. D26—14)

FIG. 3

FIG. 1

FIG. 1 is a perspective view of a telephone handset support showing my new design;

FIG. 2 is a front elevational view; and

FIG. 3 is a side elevational view, the opposite side being substantially a mirror image thereof.

The rear, not shown, is substantially a flat, unornamented surface.

The broken line showing of a handset in FIG. 1 is for illustrative purposes only.

I claim:

The ornamental design for a telephone handset support, substantially as shown and described.
